UNITED STATES PATENT OFFICE

JACOB GOLDHABER, OF JOHNSTOWN, PENNSYLVANIA

DESIGN FOR A BOTTLE OR SIMILAR ARTICLE OF MANUFACTURE

Application filed April 2, 1931. Serial No. 39,350. Term of patent 3½ years.

To all whom it may concern:

Be it known that I, JACOB GOLDHABER, a citizen of the United States, residing at 411 Third Avenue, Johnstown, in the county of Cambria and State of Pennsylvania, have invented a new, original, and ornamental Design for a Bottle or Similar Article of Manufacture.

ure 1 of the bottle, the bottle being turned approximately forty-five (45) degrees.

I claim:—

The ornamental design for a bottle or similar article of manufacture, as shown and described.

Signed at Johnstown, in the county of Cambria, State of Pennsylvania, this 30th day of March, 1931.

JACOB GOLDHABER.
